(57) **CLAIM**

The ornamental design for a necklace, as shown and described.

DESCRIPTION

FIG. 1 is a perspective view of a necklace showing my new design;

FIG. 2 is a front view of the necklace;

FIG. 3 is a left side view of the necklace;

FIG. 4 is a right side view of the necklace;

FIG. 5 is a rear view of the necklace;

FIG. 6 is a top view of the necklace; and,

FIG. 7 is a bottom view of the necklace.

Stippling shown in the drawings represents a contrast of materials from portions of the necklace which show no stippling.
